UNITED STATES PATENT OFFICE.

GEORGE L. KNOWLTON, OF PHILADELPHIA, PENNSYLVANIA.

LAWN-MOWER SHARPENER.

1,090,075.

Specification of Letters Patent. Patented Mar. 10, 1914.

Application filed May 1, 1913. Serial No. 764,833.

To all whom it may concern:

Be it known that I, GEORGE L. KNOWLTON, a citizen of the United States, residing at Philadelphia, in the county of Philadelphia and State of Pennsylvania, have invented certain new and useful Improvements in Lawn-Mower Sharpeners; and I do declare the following to be a full, clear, and exact description of the invention, such 10 as will enable others skilled in the art to which it appertains to make and use the same.

This invention relates to metal implements, and more especially to tools for 15 treating cutting implements; and the object of the same is to produce a hand tool by means of which the spiral blades of lawn mowers may be sharpened. This object is accomplished by constructing the tool in 20 the manner hereinafter more fully described and claimed, and as shown in the drawings wherein—

Figure 1 is an elevation of what might be called the front side of this tool; Fig. 2 is 25 a lower edge view thereof; Fig. 3 is a horizontal section on the line 3—3 of Fig. 1; Fig. 4 is an end view; and Fig. 5 is a vertical section on the line 5—5 of Fig. 1.

In the drawings the framework of this 30 tool is shown as composed of two parts or members, one of which is the front member 1 whose upper edge is curved inward toward the other member as at 2, whose body contains a centrally disposed and inwardly 35 projecting internally threaded boss 3, and whose lower edge has a flat inner face 4 and above it a longitudinal shoulder 5. The other or rear member 11 curves inward at its upper edge as at 12, is pierced at its center 40 for the reception of a screw 13 whose threads engage the hole in the boss 3, and near its lower edge has a shoulder 15, beneath the same a flat face 14, and beneath the latter in turn a downward projection or 45 guide 16 between whose inner edge and the face 14 said guide may be shouldered to a slight extent as at 17 so that the face 14 with the two shoulders 15 and 17 present in 50 effect a groove along the lower portion of this member 11. The upper end of this member is provided with notches 18 to receive tongues 8 at the upper end of the

member 1 when the two members are brought together by tightening up on the screw 13, and these interengaging tongues 55 and notches hold the members in proper relative position. Between their faces 4 and 14 is disposed a file 20 which is preferably square in cross section as seen in Fig. 5 and of a length equaling that of the two members as seen in Fig. 2. Attention is directed 60 to the fact that the faces 4 and 14 are disposed slightly oblique to a vertical plane through the entire tool, as seen in Fig. 4, with the result that the lowermost or working face of the file 20 stands at a slightly acute angle to the face of the guide 16.

An important feature of the present invention consists in the provision of means for overcoming excessive friction when this 70 tool is used on a lawn mower blade B, as well as means for adapting the tool to the curvature which results from the spiral or helical formation of such blade in the machines now commonly used. While the face 75 of the guide 16 is straight throughout its length, it is interrupted at its center by a notch or cutaway portion 21, and within this cutaway stands a roller 22 mounted on a screw or other pivot 23 which passes upward through it and into the lower edge of the member 11. The disposition of this pivot is such that the wearing or active face of the roller 22 projects slightly beyond the inner face of the guide 16 as seen in Figs. 2 80 and 4, with the result that when the tool is employed on a lawn mower blade having the usual curvature, if it touches the guide 16 at the extremities 24 of the latter, the roller 22 will touch said blade between such 85 extremities providing the length of the guide 16 is sufficient. The result is that the blade is firmly held by the three points of contact which the tool makes with its rear side. On the opposite side the drawing inward of 90 the lower edge of the member 1 which is effected by tightening up the screw 13 causes the face 4 to abut against one of the side faces of the file 20 so that the shoulders 5 and 15 pass above its upper face as seen in 100 Fig. 4, with the result that the lower flat face of the square file will be held at a slightly acute angle to the flat inner face of the guide 16 so as to give the proper bevel

to the cutting edge of the blade B. For holding the blade in this position while the tool is reciprocated along its edge, I provide a leaf spring 25 secured at its upper 5 end to the member 1 by a screw 26 or otherwise, passing along over the front face of the same and normally springing away from it to a slight extent as seen in Figs. 4 and 5, possessing at about its midlength a 10 slot 26' through which passes a set screw 27, and inturned at its lower end at 28 where it carries a rivet or other pivot 29 for a second roller 30 standing opposite the first roller 22. The inner end of the screw 27 15 takes into a threaded opening in the front member 1, and it is obvious that by setting up this screw the shoulder 27' thereon bears against the leaf spring 25 and throws the inner end of the latter and its roller inward 20 toward the other roller 22, or toward the guide 16 if this roller 22 is not employed, as I contemplate omitting it where the knife blade is straight.

It is well known to those who have used 25 tools of this kind that it is extremely difficult to reciprocate the file or other abrading instrument along the length of a blade B which is spiral or helical, and at the same time hold it accurately in such relative position thereto that it will sharpen the blade on a proper bevel and will maintain that bevel throughout the length of its stroke. The present tool will permit the operator to accomplish this end nicely. The spring pressure 30 of the roller 30, brought about by the spring 25 as adjusted by the set screw 27, throws the blade B against the guide 16 and its roller 22, and if the blade be thicker or thinner than as shown the set screw 27 may 35 be correspondingly adjusted. The height of the face 16 will be sufficient to maintain the entire tool in substantially the plane of the knife blade B, and the inclination of the faces 4 and 14 and therefore the disposition 40 of the lower face of the file 20 will be such that, as it is moved to and fro while the tool is reciprocated, its lower or cutting face maintains constantly the proper angle with respect to the blade to form a bevel thereon 45 as desired. The parts are by preference entirely of metal, suitably treated to prevent rust, and the details of the file are unimportant as I prefer to purchase this element from a concern which makes a specialty of 50 its manufacture. It may be that intermediate portions of the two faces 4 and 14 are cut away as seen at 35 in Fig. 2 so as to leave only two lips 36 on each face which 55 come in contact with the file at the ends of 60 the latter, because I find by experience that these files are not always perfectly straight—especially where they have been highly tempered. The size and shape of parts are immaterial to the successful operation of the 65 invention.

What is claimed as new is:

1. In a tool of the class described, the combination with a front member bent inward along its upper edge and there provided with tongues and having a face along its lower edge with a shoulder above said face and a hollow internally threaded boss about mid-way between said edges; of a rear member bent inward along its upper edge and notched to receive said tongues, 70 this member also having a face along its lower edge with a shoulder above said face and a longitudinal guide disposed beneath said face, and an aperture about mid-way between its upper and lower edges, and a screw passing through said aperture and engaging said boss. 75

2. In a tool of the class described, the combination with a front member bent inward along its upper edge and having a face along its lower edge which is cut away between its extremities, a rear member similarly constructed, and a rectangular file disposed between said faces; of interlocking elements 80 on the meeting upper edges of said members, and means between these edges and said faces for drawing the members together, for the purpose set forth. 85

3. In a tool of the class described, the combination with front and rear members abutting at their upper edges and having tool-embracing faces along their lower edges, and means between said edges for drawing said members together; of a longitudinal guide extending along the lower edge of one 90 member beneath its face, a roller opposite said guide, a spring attached to the other member and carrying this roller, and means for adjusting the tension of the spring and the position of the roller. 95

4. In a tool of the class described, the combination with front and rear members abutting at their upper edges and having tool-embracing faces along their lower edges, and means between said edges for drawing said members together; of a longitudinal guide extending along the lower edge of one member beneath its face and interrupted at its center, a roller mounted on a pin in this member and projecting through said interruption, a second roller opposite the first, a spring secured at its upper end to the other member and having its lower end in-turned and its body slotted, a pivot through said in-turned end and on which this roller 100 is mounted, and a set screw passing through said slot and into this member, for the purpose set forth. 110

5. In a tool of the class described, the combination with front and rear members abutting at their upper edges and having tool-embracing faces along their lower edges, and means between said edges for drawing said members together; of a longitudinal guide extending along the lower edge of one 115 member beneath its face and interrupted at its center, a roller mounted on a pin in this member and projecting through said interruption, a second roller opposite the first, a spring secured at its upper end to the other member and having its lower end in-turned and its body slotted, a pivot through said in-turned end and on which this roller 120 is mounted, and a set screw passing through said slot and into this member, for the purpose set forth. 125

130

member, a roller standing opposite the face of said guide, a leaf spring in whose lower end said roller is pivoted, a screw connecting its upper end with the opposite member, and 5 a set screw passing through its body and engaging this member, for the purpose set forth.

In testimony whereof I have hereunto set my hand in presence of two subscribing witnesses.

GEORGE L. KNOWLTON.
